Primary Examiner — Bao-Yen T Nguyen*Assistant Examiner* — Christopher John Suarez La Rosa(74) *Attorney, Agent, or Firm* — Bayramoglu Law Offices LLC(57) **CLAIM**

The ornamental design for a turntable, as shown and described.

DESCRIPTION

FIG. 1 is a top perspective view of a turntable showing my new design;

FIG. 2 is a front view thereof, a rear view being a mirror image of the front view;

FIG. 3 is a left side view thereof, a right view being a mirror image of the left side view;

FIG. 4 is a top view thereof;

FIG. 5 is a bottom view thereof; and,

FIG. 6 is a bottom perspective view thereof.

The broken lines depict portions of the turntable that form no part of the claimed design.

1 Claim, 6 Drawing Sheets(56)
